[57] CLAIM

The ornamental design for a multi-purpose cabinet, as shown and described.

DESCRIPTION

FIG. 1 is a perspective view of a multi-purpose cabinet showing my new design;

FIG. 2 is a front view thereof;

FIG. 3 is a rear view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a perspective view thereof from the front, top and right side.

The criss-cross shading shown only partially in all of the drawing views is understood to continue uniformly across the surfaces of the design where shown.
